UNITED STATES PATENT OFFICE.

JOHN LARSON, OF STERLING, ILLINOIS.

VEHICLE-TONGUE TIP.

No. 839,007.

Specification of Letters Patent.

Patented Dec. 18, 1908.

Application filed April 8, 1905. Serial No. 254,541.

To all whom it may concern:

Be it known that I, JOHN LARSON, a citizen of the United States, residing at Sterling, in the county of Whiteside, State of Illinois, have invented certain new and useful Improvements in Vehicle-Tongue Tips; and I do hereby declare the following to be a full, clear, and exact description of the invention, such as will enable others skilled in the art to which it appertains to make and use the same.

This invention relates to vehicle-tongue tips.

One object of the invention is to provide means for protecting the outer or free end of a wagon or other vehicle tongue and to so construct the tip as to provide means for positively locking the neck-yoke in place.

Another object of the invention resides in the provision of an exceedingly simple, inexpensive, durable, and efficient means to protect the outer or free end of the vehicle-tongue and to so construct and arrange the elements comprising the tip as to provide for the ready insertion and support of a neck-yoke.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the present invention.

In the drawings, Figure 1 is a side elevation of a portion of a tongue having my improved device secured thereto. Fig. 2 is a sectional view. Fig. 3 is a detail perspective view of the pivoted member. Fig. 4 is a detail perspective view of the rectangular-shaped rivet having a flat head and to which the pivoted member is connected.

Referring now more particularly to the accompanying drawings, the reference character 1 designates the free or outer end of a vehicle-tongue of any construction, secured to the extremity of which is a tip of metal or other suitable material. The metal forming the tip is bent back upon itself to form the upper and lower members 2 and 3, the bent portion 4 extending beyond the extremity of the tongue to provide an eye 5 for the reception of a strap of the neck-yoke in the usual

manner. The tip is secured to the tongue through the instrumentality of rivets or the like 6, 7, and 8, and each member 2 and 3 is provided near its free end with rectangular-shaped openings 9 and 10, respectively, which are designed to align for the reception of a rectangular-shaped rivet 11, which latter pierces the extremity of the tongue 1 and has an enlargement forming the head 12 and shoulders 13, the head having a perforation 14 therein and its shoulders designed to engage the under face of the member 3 of the pole.

As clearly shown in the drawings, the member 3 of the tip is bent upon itself to form a downwardly-inclined extension 16, upon the upper surface 16' of which the free end of a dog 17 is designed to be supported over the bent portion 16' of the said extension, the dog or pivoted member 17 having one end enlarged and bifurcated to form wings 18, designed to overlap the head 12 of the square rivet 11, which head is flattened longitudinally with respect to said tip and to be pivoted thereto through the instrumentality of a pivot-pin 19, designed to pierce the wings and pass through the opening 14 in the head 12. By reason of the peculiar engagement of the member 17 to the flat head 12 sidewise or lateral movement of the dog or member 17 is prevented. It will thus be seen that the free end of the member 17 cannot fall below the extremity of the extension 16, but that it can be lifted from engagement with the latter to permit of the insertion of the neck-yoke (not shown) and that as soon as the neck-yoke is pushed upon the face 16' of the extension 16 the dog member 17 will fall to its normal position and positively retain the neck-yoke there between the extension and the member 3 of the tip, as should now be clearly understood. It will be noted that the members forming an extension 16 are spaced apart to a slight extent to provide for more or less resiliency.

In the use of my improved invention it is obvious that in the event horses should become excited and attempt to back there is absolutely no danger whatever of the yoke leaving its seat upon the extension 16 of the tip and that the yoke cannot leave the extension in the forward direction by reason of the free end of the dog 17 being inclined and riding upon the upper surface 16' of the extension 16. In other words, it will be seen that the yoke will be positively locked in its seat.

What is claimed is—

1. A device of the kind described comprising a tip formed of a single strip of metal bent upon itself to form upper and lower spaced members between which the vehicle-tongue is adapted to be secured, the said lower member being in turn bent upon itself to form a forwardly and downwardly inclined extension; a rivet passing through said upper and lower members and said vehicle-tongue in advance of said extension, said rivet having an enlarged flattened lower head; and a rearwardly-extending dog provided at its forward end with a pair of spaced wings adapted to receive said rivet-head therebetween, and connected therewith, the opposite end of said dog being adapted to normally rest upon the upper surface of said downward extension.
2. A device of the kind described, comprising in combination with a vehicle-tongue, a tip formed of a single strip of metal bent upon itself to form upper and lower members between which said tongue is adapted to be secured,

said lower member being bent upon itself 25 intermediate its ends to form a forwardly and downwardly inclined extension, said upper and lower members and said tongue being provided with registering rectangular perforations disposed in advance of the front end 30 of said extension; a rivet passing through said perforations and provided with an enlarged lower head flattened longitudinally of said members, the inner face of said head being in contact with the outer face of said 35 lower member; and a rearwardly-extending dog provided at its forward end with a pair of spaced wings adapted to receive said rivet-head therebetween and connected therewith, the opposite end of said dog being adapted 40 to normally rest upon the upper surface of said downward extension.

In testimony whereof I affix my signature in presence of two witnesses.

JOHN LARSON.
